UNITED STATES PATENT OFFICE

WILLIAM J. DE WITT, OF AUBURN, NEW YORK, ASSIGNOR TO SHOE FORM CO., INC., OF AUBURN, NEW YORK, A CORPORATION OF NEW YORK

DISPLAY DEVICE

Application filed March 12, 1931. Serial No. 521,983.

This invention relates to an improvement in a display device and more particularly in a device for displaying boats or other articles adapted to be carried by water or other liquid.

5 The primary object of this invention is to provide a display device comprising a tank having one or more compartments adapted to contain liquid in which articles to be displayed are carried and means for setting in motion the liquid in one or more of the compartments thus imparting movement to the articles carried thereby.

10 A further object of this invention is to provide a display device comprising a tank having a plurality of compartments each containing liquid in which articles carried by the liquid are given movement of translation by setting the liquid in the various channels in motion, preferably of circulation in 15 different directions, so that the moving articles will attract the attention of the passersby.

Other objects of the invention will appear 20 from a consideration of the following specification and of the drawing which forms a part 25 thereof and in which

Fig. 1 is a plan view of a display device embodying one form of this invention;

Fig. 2 is a sectional view of the device with parts broken away; and

30 Fig. 3 is an enlarged sectional view of one detail of the invention.

In the embodiment shown in the drawing, which was selected for illustration and not for limitation, the display device 10 comprises 35 a tank 11 cylindrical in form supported upon uprights 12. Mounted on the base 13 of the tank are partitions 14 which with the outer wall 15 divide the tank into a plurality of compartments. The compartments of the illustrated device are four in number, designated respectively 16, 17, 18 and 19. The 40 partitions 14 and wall 15 are annular and concentric so that the compartment 16 is surrounded by annular compartments 17, 18 and 19.

The tank is partially filled with water or other liquid thus providing a central body of liquid surrounded by separate annular bodies or channels of liquid. In order to attract 45 attention, I propose to set up a circulation of

the liquid in the compartments. In the present embodiment the liquid in compartments 16 and 18 travels in a clockwise direction and the liquid in compartments 17 and 19 travels in a counterclockwise direction, such directions to be indicated by the arrows 20 in Fig. 1. The liquid may be set in motion by any suitable means as for example a centrifugal pump 21 driven by a motor 22 and having an intake pipe 23 and an outlet pipe 24. The 55 intake pipe 23 is substantially Y-shaped as shown in Fig. 1, the leg 25 being connected to channels 16 and 18 and the leg 26 being connected to channels 17 and 19 through openings 27 in the base 13. The outlet pipe 24 is connected to each compartment through an opening 28 which, as shown in Fig. 3, is partially covered by a shield or hood 29. It will be noted that the hood 29 in each compartment faces in the direction of the current set 60 up therein and that the opening 27 is behind the opening 28.

In the risers connecting the openings 27 and 28 with the intake and outlet pipes are provided valves 30 by which the flow of liquid 65 is controlled. The base 13 and wall 15 of the tank and the partitions 14 may be of transparent, translucent or opaque material. The top of the tank 11 may be closed by a plate 31 preferably of glass or other transparent material or may be left open in order 70 to permit the articles carried by the bodies of liquid to project above the wall 14.

This particular embodiment is intended to 75 be used to display boats or other water craft placed in the various compartments of the tank. When the pump 21 is set into operation by the motor 22 a portion of the liquid in each compartment is drawn through the openings 27 to the intake pipe 23 and returned 80 to the compartments by the outlet pipe 24 and openings 28. The returned liquid passing into the compartments in the direction determined by the hoods 29 will obviously 85 keep the liquid in motion in the desired directions. By means of the valves 30 the amount of liquid withdrawn from and returned to each compartment is determined and the speed of circulation regulated as desired. 90 The boats in the various compartments will 95 100

thus be given movements of translation in the tank and will attract attention thereto.

While one embodiment of this device has been shown and described and its use in displaying boats has been mentioned, it will be understood that I am not limited to such specified embodiment and use since other embodiments and uses may be made without departing from the spirit and scope of this invention as set forth in the following claims.

I claim:

1. A display device comprising a tank having a circular wall and a plurality of partitions concentric with the wall to define an inner compartment and a plurality of annular compartments surrounding the inner compartment and each compartment containing liquid and means for setting the liquid in the various compartments in motion.
2. A display device comprising a tank having a circular wall and a plurality of partitions concentric with the wall to define an inner compartment and a plurality of annular compartments surrounding the inner compartment, each compartment containing liquid, and a pump adapted to withdraw a portion of the liquid from each compartment and return liquid thereto thereby setting the liquid in the compartments in motion.
3. A display device comprising a tank having a circular wall and a plurality of partitions concentric with the wall to define an inner compartment and a plurality of annular compartments surrounding the inner compartment, each compartment containing liquid by which articles are carried and means for setting the liquid in the compartments in circulation and thereby imparting motion to the articles carried thereby.
4. A display device comprising a tank having a circular wall and a plurality of partitions concentric with the wall to define an inner compartment and a plurality of annular compartments surrounding the inner compartment, each compartment containing liquid, a pump having an intake pipe and an outlet pipe and connections between each compartments and said pipes whereby the pump withdraws a portion of the liquid from each compartment and returns liquid thereto thereby setting the liquid in the compartments in motion.
5. A display device comprising a tank having a circular wall and a plurality of partitions concentric with the wall to define an inner compartment and a plurality of annular compartments surrounding the inner compartment, each compartment containing liquid, a pump having an intake pipe and an outlet pipe and connections between each compartments and said pipes whereby the pump withdraws a portion of the liquid from each compartment and returns liquid thereto thereby setting the liquid in the compartments in motion, and means associated with

the outlet pipe connections for sending the liquid returned to the compartments in a predetermined direction.

6. A display device comprising a tank having a circular wall and a plurality of partitions concentric with the wall to define an inner compartment and a plurality of annular compartments surrounding the inner compartment, each compartment containing liquid, a pump having an intake pipe and an outlet pipe and connections between each compartments and said pipes whereby the pump withdraws a portion of the liquid from each compartment and returns liquid thereto thereby setting the liquid in the compartments in motion, and means associated with the outlet pipe connections for sending the liquid returned to certain of said compartments in one direction and the liquid returned to other of said compartments in another direction.

7. A display device comprising a tank having a circular wall and a plurality of partitions concentric with the wall to define an inner compartment and a plurality of annular compartments surrounding the inner compartment, each compartment containing liquid, a pump having an intake pipe and an outlet pipe and connections between each compartments and said pipes whereby the pump withdraws a portion of the liquid from each compartment and returns liquid thereto thereby setting the liquid in the compartments in motion, and hoods in each compartment associated with the outlet pipe connections for sending the liquid returned to the compartments in a predetermined direction.

8. A display device comprising a tank having a circular wall and a plurality of partitions concentric with the wall to define an inner compartment and a plurality of annular compartments surrounding the inner compartment, each compartment containing liquid, a pump having an intake pipe and an outlet pipe and connections between each compartments and said pipes whereby the pump withdraws a portion of the liquid from each compartment and returns liquid thereto thereby setting the liquid in the compartments in motion, and hoods in each compartment associated with the outlet pipe connections for sending the liquid returned to certain of said compartments in one direction and the liquid returned to other of said compartments in another direction.

Signed by me at Auburn, N. Y., this 10th day of Mar., 1931.

WILLIAM J. DE WITT.
